Primary Examiner—B. J. Bullock

(74) Attorney, Agent, or Firm—Atkin, Gump, Strauss,
Hauer & Feld, L.L.P.(57) **CLAIM**

The ornamental design for a knob, as shown and described.

DESCRIPTION

FIG. 1 is a front perspective view of a knob in accordance with a first preferred embodiment of my new design;
FIG. 2 is a right side elevational view thereof, a mirror image of which is a left side elevational view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a front perspective view of a knob in accordance with a second preferred embodiment of my new design;
FIG. 8 is a right side elevational view thereof, a mirror image of which is a left side elevational view thereof;
FIG. 9 is a front elevational view thereof;
FIG. 10 is a rear elevational view thereof;
FIG. 11 is a top plan view thereof; and,
FIG. 12 is a bottom plan view thereof.

The broken lines showing the rear portion of the knob is for illustrative purposes only and forms no part of the claimed design.
